UNITED STATES PATENT OFFICE.

SIDNEY M. WEATHERLY, OF PHILADELPHIA, PENNSYLVANIA.

DESIGN FOR A FONT OF TYPE.

No. 39,718.

Specification for Design.

Patented Dec. 22, 1908.

Application filed October 16, 1907. Serial No. 397,753. Term of patent 14 years.

To all whom it may concern:

Be it known that I, SIDNEY M. WEATHERLY, a citizen of the United States, residing at Philadelphia, in the county of Philadelphia and State of Pennsylvania, have invented a certain new, original, and ornamental Design for a Font of Type, of which the following is a specification.

The accompanying drawing, which is made a part hereof and to which reference is made, shows the face and form of each letter and character composing said font of type, as well as the ornamental character of the font as a whole.

What I claim is:

The ornamental design for a font of type shown in the accompanying drawing.

Correction in Design Letters Patent No. 39,718.

It is hereby certified that in Design Letters Patent No. 39,718, granted December 22, 1908, upon the application of Sidney M. Weatherly, of Philadelphia, Pennsylvania, for a Design for a "Font of Type," an error appears in the printed specification requiring correction as follows: Second column, after line 6, the paragraph In witness whereof I have hereunto set my hand and seal at Philadelphia, Pennsylvania, this 15th day of October, A. D. nineteen hundred and seven should be inserted; and that the said Letters Patent should be read with this correction therein that the same may conform to the record of the case in the Patent Office.

Signed and sealed this 14th day of March, A. D., 1911.

[SEAL.]

E. B. MOORE,

Commissioner of Patents.
